DESIGN FOR A COMBINED HANGER AND DEODORANT CONTAINER

Helen de Benque, New York, N. Y.

Application October 21, 1937, Serial No. 72,348

Term of patent 3½ years

To all whom it may concern:

Be it known that I, Helen de Benque, a citizen of the United States of America, residing in New York city, in the Borough of Manhattan, county and State of New York, have invented a new, original, and ornamental Design for a Combined Hanger and Deodorant Container, of which the following is a specification, reference being had to the accompanying drawing, forming part thereof, wherein,

Figure 1 is a front view of a combined hanger

and deodorant container showing my new design.

Figure 2 is a bottom plan view thereof, and

Figure 3 is a side elevational view of the combined hanger and deodorant container shown in Figure 1.

I claim:

The ornamental design for a combined hanger and deodorant container, substantially as shown.

HELEN DE BENQUE.
